United States Patent Office.

JAMES P. SPAULDING, OF WILLIAMSPORT, PENNSYLVANIA.

Letters Patent No. 105,009, dated July 5, 1870.

IMPROVEMENT IN WELL-FILTERS.

The Schedule referred to in these Letters Patent and making part of the same

To all whom it may concern:

Be it known that I, JAMES P. SPAULDING, of the city of Williamsport, in the county of Lycoming and State of Pennsylvania, have invented a new and useful Apparatus for Filtering and Purifying Water in Wells, and for fastening the sections of pump-stocks together, and supporting and strengthening the joints thereof; also, a device for preventing the suckers of pumps from wearing away—all of which I term an improvement in wells.

Figure 1 is a side view of a pump, embodying my improvements.

Figure 2, a perspective side and bottom view of the lower section of the water-chamber.

Figure 3 is a perspective top view of a disk, with filtering-tubes therein.

Figure 4 is a reversed view of the same.

Figure 5 is an edge view of the same.

Figure 6 is a sleeve, surrounding a pump-sucker.

Figure 7 is a perspective top view of the clamps for fastening the sections of a pump-stock together.

Figure 8 is a pipe for admitting air to the water-chamber A.

A is the water-chamber, and may be constructed of stone-ware, or other durable material, and is to be placed in the bottom of old or new wells, for the purpose of filtering and purifying the water therein, the said chamber to be constructed in any desired number of sections, with a perforated bottom, B, and disk, F, with filtering-tubes c c c. The perforated bottom B is placed in the lower section of the water-chamber A, about five inches within the section.

The disk F, containing the filtering-tubes c c c, rests within the lower section of the said water-chamber A, leaving a space of four inches between the bottom B and the disk F.

The lower end of the water-chamber A is to be either slotted or perforated with round holes, both above and below the bottom B, as shown in fig. 2, for the purpose of admitting the water into the said chamber A, below the disk F, the said disk F, or figs. 3, 4, and 5, being constructed with any desired number of small perforated tubes c c c, as shown in fig. 4, through which the water rises from the well into the water-chamber A, and from whence it flows into the pump-stock C, through the conductor D, as shown in fig. 1. The pump-stock C and conductor D to be made of stone-ware, or other durable material.

The pump-stock to be made in sections, and securely fastened together by means of the clamps E E E, as shown in fig. 1.

The said clamps to be made of galvanized iron, or

other indestructible metal, with rods and screw-nuts, as shown in fig. 4, by means of which the sections of a pump-stock may be securely fastened together, the clamps E E E resting against the shoulders O O on the sections of the pump-stock C, as shown in fig. 1.

g g, in fig. 6, is a sleeve for the sucker, on the lower end of the piston, to move or work in, the said sleeve to be made of porcelain, or other smooth substance, with an ordinary valve in the lower end thereof, the said sleeve to be inserted down into the pump-stock, from the upper end, to a shoulder or offset in the pump-stock, for the said sleeve to rest on, and where it can be securely held by pins or screws. The purpose of the said sleeve g g is first to enable the valve, which is part of the sleeve, to be drawn from the pump-stock without removing any part of the said stock; and, second, for the purpose of preventing the sucker from wearing away as rapidly as it otherwise would if exposed to the rough surface of the pump-stock.

U, in fig. 8, is an air-pipe, with a perforated ball on the upper end, the lower end being inserted in the crown of the water-chamber A, for the purpose of conducting air from the surface down to the water-chamber, in order to facilitate pumping the water therefrom.

The manner of putting my apparatus and pump into wells is simple and practical.

When the well is sunk to a proper depth, I put clean, coarse gravel, or charcoal, or both mixed together, in the bottom of the well. I then put in the water-chamber A, with the perforated bottom B, and the disk F, in their places, resting them on the gravel or charcoal in the bottom of the well. I then attach the pump-stock C to the conductor D, as shown in fig. 1, and insert the air-pipe U in the crown of the water-chamber A, as shown in fig. 1. I then cover up the said water-chamber A with coarse gravel or charcoal, and then fill up the well to the surface with earth, thus preventing the surface water and other unclean matter from mingling with the water in the well.

I claim as my invention—

The combination, with the water-chamber A and perforated bottom B, the filtering-tubes c c c of the disk F, and the conductor D, substantially as and for the purposes herein set forth.

JAMES P. SPAULDING.
